FIG. 4.

UNITED STATES PATENT OFFICE

2,668,214

FUSE CUTOUT

Oliver A. Vordtriede, St. Louis, Mo., assignor, by
mesne assignments, to A. B. Chance Company,
Centralia, Mo., a corporation of Missouri

Application February 9, 1953, Serial No. 335,943

5 Claims. (Cl. 200—117)

1

This invention relates to fuse cutouts, and more particularly to a fuse cutout which is an improvement upon the cutout shown in the United States application Serial No. 229,814 of James J. Cooper and myself, filed June 4, 1951, for Fuse Cutout.

Among the several objects of the invention may be noted the provision of independently functioning tensioning and withdrawal means for a contained fuse link, which incorporates a latch adapted to prevent additional tensioning of the fuse link as has heretofore been caused by reaction pressure from a lower spring contact; and the provision of an improved form of lower spring contact having a wiping action upon release. Briefly, the above ends are accomplished by arranging a pivoted and biased link-tensioning device with a latch which coordinates with a double-pivot member to relieve the link from said reaction. The surfaces of the lower spring contact and of the line terminal block with which it engages cooperate over an arc, providing for wiping action upon movement of the spring contact from the terminal block.

The invention accordingly comprises the elements and combinations of elements, features of construction, and arrangements of parts which will be exemplified in the structures hereinafter described, and the scope of which will be indicated in the following claims.

In the accompanying drawings, in which one of various possible embodiments of the invention is illustrated,

Fig. 1 is a side elevation of my fuse cutout in its condition immediately prior to rupture of the fuse, the housing being shown in section, parts of the fuse holder being broken away, the position of parts after drop-down operation being shown in dotted lines;

Fig. 2 is an idealized front elevation of the housing and fuse holder after drop-out operation, as viewed from lines 2—2 of Fig. 4;

Fig. 3 is a view similar to that of Fig. 1, showing the position of parts after pop-out operation;

Fig. 4 is a view similar to that of Fig. 1, showing the position of parts after drop-out operation, a position of certain parts during removal of the fuse holder being indicated by dotted lines;

Fig. 5 is an enlarged detail section taken on line 5—5 of Fig. 3; and,

Fig. 6 is a detail cross section taken on line 6—6 of Fig. 3.

Similar reference characters indicate corresponding parts throughout the several views of the drawings. Reference characters above 200 show the parts which constitute the departure from the construction shown in said application Serial No. 229,814. Figs. 2—4 are on a reduced

2

scale and Figs. 5 and 6 are on enlarged scales, all relative to Fig. 1.

Referring to the drawings, there is shown in Fig. 1 a fuse cutout of this invention as mounted on a power-line pole. The cutout is of the enclosed type having a fuse support comprising a housing 1 of porcelain, and upper and lower interior line terminal elements 3 and 5, respectively, carried by the housing. A fuse holder is 5 removably supported upon the housing or fuse support. This fuse holder comprises a door 7 for the housing, a fuse tube 9 fixed to the door, and upper and lower terminal-engaging contact members 11 and 13, respectively. The door 7 is supported upon the housing 1 by a movable hinge or double-pivot member 15, pivotal at 17 to the door and removably hinged on pivots 19 to hinge sockets 20.

A hanger 21 is affixed, as by cement 23, to the 20 housing for mounting it, as upon the crossbar of a line pole, at an angle such that the top of the housing and center of gravity of the fuse holder are overcentered with respect to the open bottom 25 of the housing and pivot 19, respectively.

The door 7 is formed at its top with an eye 27 25 so that it may be opened and closed by means of the usual lineman's "hot" stick. On the inside, the door 7 is formed with upper and lower apertured projections 29 and 31 respectively. These

30 receive the fuse tube 9. The fuse tube 9 is fixed within the apertured projections by means of a retaining pin 33 extending through the lower projections 31 and cooperating with a suitable recess in the fuse tube. The fuse tube 9, which

35 is formed of insulating material such as wrapped plastic and fiber, is closed at its top by an assembly of conductive parts forming the upper contact member 11. Threaded upon the tube at its top is a collar 35, which bears against a lock washer 37. The collar is apertured at 39 to

40 receive a fuse link 41. The fuse link 41 has a head 43 which seats against the top of the collar 35. Threaded over the collar and against the head 43 of the fuse link is a thumb cap 45.

45 When the door 7 is closed, the cap 45 is surrounded on opposite sides by conductive spring contact clips 47. These clips 47 have inwardly divergent portions 49 (Figs. 2 and 3) adapted releasably to retain the door closed and to exert

50 a rearward bias upon the fuse holder. The top of the cap is engaged by a conductive spring contact wiper 51 having a loop portion 53, a flat portion 55 normally seating against the top of the contact of the cap 45 and a lip portion 57 normally overhanging the top of the cap 45 for latching purposes. A resilient bracing clip 58 55 engages the top of the wiper 51.

The clips 47, 51 and 58 are fixed upon an upper electrically conductive terminal block 59, which 60 is cemented to the housing. The terminal block

59 is provided with line-connection means having a line-receiving groove 61, opposite from which is a resilient antiscratch bar 63. The bar 63 is self biased away from the groove 61 to facilitate entry of a conductor (not shown), and is moved toward the groove 61 by a screw 65 to seat a conductor firmly in the groove. The housing 1 has side apertures 67 which permit entry of a line conductor. The terminal block is more particularly described and claimed in the co-pending application of James J. Cooper entitled Terminal Block, Serial No. 223,731, filed April 30, 1951.

It will be apparent that an electrical connection is provided from the terminal block 59 through the spring clips 47 and 51 and through the conductive cap 45 to the head of the fuse link. The fuse link 41 extends through and out of the open bottom end 71 of the fuse tube 9, and has a fusible element 69 located within the tube 9. Telescoped over the lower end of the fuse tube 9 is a copper sleeve or indicator tube 73, which carries an upper collar 75 and a lower collar-like member 77. A guide plate 79, secured between the upper and lower collars 75 and 77, slides within a guide recess 81 formed in the back of the door. A transverse stop plate 83 is secured over the guide recess 81 to prevent the indicator tube 73 from dropping off the fuse holder. The indicator tube 73 is biased from a retracted position within the housing to an extended position (dotted lines of Fig. 1). A coil spring 85 is telescoped over the fuse tube 9 so as to abut against the lower door projection 31, an isolating member of insulating material 87 resting on top of the upper collar 75.

The lower collar or supporting member 77 is provided with an arm 89 of right-angular conformation. Fixed on the arm 89 is a spring brush 201 of arcuate form for contact with an arcuate conductive portion 203 of the lower line terminal 5, which includes a terminal block 92 similar to the upper terminal block 59. The arcuate contact surface of the brush 201 faces in an upward direction and away from the fuse holder. The arcuate contact surface of portion 203 faces in the opposite direction. When the lower contact member is in its retracted (upper) position, a force is developed between the brush 201 and the contact portion 203 which tends to drive the lower contact member downward and the fuse holder outward. When release occurs under drop-down, pop-out or drop-out conditions to be described, a rotary action is imparted to the spring brush 201, which wipes over the portion 203 as it recedes therefrom. This constitutes one improvement upon the construction shown in said application Serial No. 229,814.

As will appear below, the lower contact member 89 is held in its retracted (upper) position by attachment of an unbroken fuse link 41 to a binding post 93 extending from the arm 89. A thumb screw 95 is threaded over the binding post and carries a washer 98 which holds down a hand-formed loop at the end of the link.

The movable member 15 upon which the fuse holder is pivotally supported is a member formed with a central body 97 normally located behind the fuse tube 9 and in front of the arm 89. Keyholes 99, adapted for cooperation with a "hot" stick, are located on opposite sides of the body 97. Extending from the body on opposite sides of the fuse tube 9 are legs 101 carrying trunnions 103. The trunnions are removably received within upwardly opening hook members 105 ce-

mented in the sides of the housing at the open bottom 25. Projecting from the body 97 of the movable double-pivot member 15 in an opposite direction from legs 101 are arms 107, which are pivoted upon a pin 109 set in lobes 111 formed on the door. When the door is closed, the member 15 assumes a generally upright position closely around the indicator tube 73.

With the lower contact member 13 in its retracted position, a step 113 formed thereon cooperates with a shoulder step 115 on the member 15 to retain it in its stated upright position. Steps 113 and 115 in effect function as a latch for preventing the member 15 from rotating relative to the fuse holder on the pivot 17, while permitting rotation on the pivot at 19. This latch is released upon movement of the lower contact member from its retracted position.

At 205 on arm 89 is pivoted a link-tensioning member 207 which consists of a plate 209 having side arms 211 through which the pivot 235 passes. This plate carries a saddle portion 213 over which the fuse link 41 may be turned, and also ears 215 between which it may be located. The side arms 211 include hooks 217 for engagement over a catch 219 formed as a bridging portion between opposite sides of the step 115. A spring 221, wound on the pivot 205, reacts from the tube 73 on the one hand and against the plate 209 on the other hand. This biases the member 207 clockwise (Figs. 3 and 4). However, the member 207 may be moved manually into the position shown in Fig. 1 after the tube 73 is moved up, so as to place the hooks 217 over the catch 219. The member 207 may then be bound in this position by threading the fuse link 41, as shown in solid lines in Fig. 1, and anchoring it by nut 95 after looping it around member 93. At this time the arm 89 is in its upward position, latching the member 15 at latch 113, 115. Then when the door 7 is closed, the reaction from spring 201 on the door assembly will not be transmitted to the fuse link 41, as was the case of the construction in said application Serial No. 229,814. This is because the force from the spring 201 is transmitted through the member 89, pivot 205, and hooks 217 to member 15 without being transmitted through the link 41. The only tension on the fuse link 41 is that provided by the clockwise biasing action of spring 221 on the link-tensioning member 207. In other words, in the present construction, as distinguished from that shown in said application Serial No. 229,814, the lighter force of the spring 221 alone tensions the link, rather than the heavier force from the contact spring 201.

The rotational movement of the member 15 relative to the door 7 is also controlled by an indicator selector member in the form of a plate 117 carried on one of the arms 107 of the member 15. This plate is pivoted on the hinge pin 109 and has an arcuate opening 119 lying on a circle concentric with the hinge pin and may be provided with three enlargements designated DO, PO and DD, reading in a counterclockwise direction as viewed in Fig. 1. The plate 117 is adjustably fixed with respect to the member 15 by means of a screw 121 threaded into the arm 107. A shoulder 123 on the screw 121 is adapted to fit within a selected one of the three enlargements DO, PO and DD, thereby locking the plate against rotation on the hinge pin 109. In Fig. 1, the screw is shown to be fitted within the enlargement DD, but it will be understood that when the screw is partially unscrewed so as to withdraw its shoulder

123 from the recess DD, the plate may be rotated to either of the other two positions and fixed in position by again tightening the screw.

The particular position of the selector plate on the member 15 is important in this respect. As shown in Figs. 1, 3 and 4, the plate has an edge 125 facing the back of the door 7. The amount of rotation of the member 15 relative to the door is therefore determined by the engagement of the edge 125 of the selectively positionable plate with the back of the door. With the indicator selector plate in the DD position (screw 121 located in the enlargement DD), the member 15 cannot rotate relative to the door 7 even though the latch at 113 and 115 is released. With the indicator selector plate in the PO position, limited free anticlockwise rotation of the member 15 relative to the door may occur. With the indicator selector plate in the DO position, relatively greater free clockwise rotational movement of the member 15 relative to the door is possible.

When the apparatus is set for PO or DO operation, the member 15 swings outward from the upright position shown in Fig. 1 and the lower part of the door is carried outward as shown in Figs. 3 and 4, respectively. The top portion of the door is beveled at its edge as indicated at 127 to permit this movement. An edge 129 of the door 7 otherwise is flat and abuts against a recessed door seat 131 in the front of the housing 1.

Operation is as follows:

Assume first the door 7 has been closed and the indicator selector stop 117 is set for drop-down (DD) operation. The lower contact member 13 is held in its retracted position by the hooks 217 on catch 219. This holding action occurs against the expansive action of spring 85 and downward reaction of spring 201. None of these actions are transmitted to the fuse link 41. The latch at 113 and 115 prevents rotation of the member 15 relative to the door 7. The selector plate 117 also prevents such rotation. The door is biased in an outward and downward direction by the engagement of the contact spring 201 with the arcuate member 203. There is also a similarly directed gravity bias resulting from the location of the door on the inclined fuse housing 1. Also, an additional downward component of bias is imparted to the door by the wiper clip 51 and associated spring brace 58 bearing against the top of the upper contact member 11. None of these biases are applied to the link 41. The only bias on it is that due to bias of spring 221 on pivot member 207.

The fuse holder is retained in position by means of the trunnions 103 seated in the hook members 105, and by the latching engagement of spring clips 47 and 52 with the cap 45 at the top of the fuse tube 9. The clips merely prevent outward movement of the top of the fuse holder. This latching cooperation at the top of the fuse holder is sufficient to hold against the outward thrust from 201 and 203, which thrust acts intermediately of the holding effect of the contact member within the clips 47 and 51 and the reaction of the trunnions 103 in the hook members 105.

When the fuse blows upon passage of an excessive current, there may or may not be developed an explosive discharge tending to drive the lower fragment of the fuse link through the open bottom end of the tube. In any event, the link-tensioning member 207 is then released to rotate clockwise, which aids in withdrawal of the lower part of the link 41. This also releases the hooks 217 from the catch 219. Then the reac-

tive force between members 201 and 203 and expansion of the spring 85, aided by gravity, drives down the lower contact member 13. Since the lower contact member 13 and the attached segment

5 of the fuse link move as a unit, this segment, even though relatively stiff, is positively withdrawn. If the link is flexible enough or the explosive force (if it occurs) is sufficient, it may reach the position shown by dotted lines at the bottom of Fig. 10 1. In either event operation is positive.

Upon the parting of the fuse, as mentioned before, the lower contact member 13 is driven from its retracted position to an extended position, the contact member being guided downward by the

15 guide plate 79 sliding within the guide recess 81 on the door and by the telescoping cooperation of the indicator tube 73 with the fuse tube 9. The extended position of the lower contact is determined by the engagement of the upper collar 75

20 on the indicator tube with the stop plate 83. When the lower contact member 13 reaches its lower extended position, the spring 201 has been wipedly separated from 203, so that the lower contact member and fuse fragment are electrically dead. Also, the lower contact member projects from the bottom of the housing, thereby providing visual indication of the outage. This constitutes drop-down operation. Although movement of the lower contact member results in

30 a release of the latch at 113 and 115, rotation of the member 15 relative to the door 7 is prevented by the indicator selector plate 117. Consequently, the door 7 remains in its closed position, being held there by the latching cooperation of the upper contact 11 with the upper terminal element 3. A replacement of the blown fuse link is achieved by opening the door by means of the eye 27 and lifting the door from the housing 1, as will be explained.

40 Assume next that the door is closed with an unblown fuse link mounted therein and that the indicator selector plate 117 is set for pop-out (PO) operation. The sequence of movements is similar to that described heretofore with the exception below noted. When the lower contact

45 member begins its downward movement from its retracted position upon blowing of the fuse, the latch at 113 and 115 is released before the spring brush 201 completely leaves the member 203. Therefore, an outward reaction is imparted to

50 the lower portion of the fuse holder by the engagement of members 201 and 203. This force, also aided by the weight of the door, drives the fuse holder and door 7 outward so that the door in effect rotates upon the hinges at pivots 17 and

55 19. Outward movement of the top of the door is restrained by the latching cooperation of the spring clips 47 and 51 with the upper contact member 11, although swinging pop-out movement of the lower part of the door is permitted by the

60 beveled portion 127 at the top of the door. Therefore, the lower portion of the door partially pops out to a limited extent of the housing. The amount of outward movement is limited by the engagement of edge 125 of the indicator selector plate 117 with the back of the door 7, as indicated in Fig. 3. This outward movement of the lower portion of the door is readily visible, yet also to a large extent the inside of the cutout is protected from weather such as sleet and icing conditions. Therefore, a second visual indication of the outage is given, it being understood that the lower contact member has also dropped so as to project below the bottom of the housing. This is known herein as pop-out operation.

65 Assume next that the cutout is set for the drop-

out (DO) operation. The movement of parts is the same as described above, with the exception that the selector plate 117, having been readjusted with the screw 121 at the DO position, allows further outward movement of the door at its lower portion. As the member 15 swings outward upon the pivot at 19, the door 7 also drops. When the door drops, the cap 45 at the upper contact member 11 is withdrawn downward from the latching cooperation of the spring clips 47 and 51, and when this latch is released the upper part of the door falls open under gravity bias to the position indicated at Fig. 4. The final position of the door is determined by the engagement of its lower edge with the lower side edges of the housing 1. The housing is otherwise recessed at its lower portion to permit the lower contact member to swing upward within the housing. This is known as drop-out operation.

Referring to Fig. 4, the split trunnions 103 have their flat surfaces 133 positioned such that when the door is hanging in its open position it may not be removed by upward movement on the door or upper contact as might occur if a lineman were accidentally to brush against the door in climbing the line pole. A slight upward swinging movement of the member 15 must first occur to clear the trunnions for lifting movement from the hooks 105. This slight upward swinging movement is automatically obtained by application of a hot stick to one of the keyholes 99. The complete fuse holder may then be removed from the fuse support and the blown fuse link may be readily replaced.

A new fuse link is inserted by removing the cap 45, threading the fuse link through the fuse tube 9 and securing the outer end of the fuse link at the binding post 93. At this time the link-tensioning member 207 is moved counterclockwise against the action of spring 221 and the hooks 217 are moved into position over the catch 219. This tensions the link. The fuse holder is then replaced upon the housing by use of keyholes 99 and the door closed by use of eyelet 27. It will be noted that door 7 may be closed without replacing the fuse link 41 and maintained closed by adjusting the selector plate 117 to the DD position. The lower contact member 13 will project from the housing to furnish indication that the cutout is not fused while the conductive parts are protected from weather.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. A fuse cutout comprising a support having upper and lower line terminals, a double-pivot member pivoted to the support at one of its pivots, a fuse holder pivoted to said double-pivot member at its other pivot, an upper contact member on the fuse holder, a lower contact member slidably mounted upon the fuse holder for longitudinal movement thereof from a retracted position to an extended position, said lower contact member being conductively engageable with the lower line terminal, means latching the double-pivot member by the lower contact member when the latter is in its retracted position, means for holding a fuse link between the upper and lower contact members to retain the lower contact

member in its retracted and latching position, a link-tensioning member pivoted on the lower contact member and having a fusé-engaging end, said double-pivot member having a catch and 5 said link-tensioning member having holding means engageable with the catch in a retracted position of the lower contact member and adapted to be held in engagement by an unbroken fuse link, and spring means biasing said link-tensioning member to move in a direction to tension the fuse link and to release said holding means from said catch when the link is severed.

2. Apparatus made according to claim 1, wherein the lower line terminal includes a nonresilient 15 conductive portion and wherein said lower contact member includes an arcuate spring which is engageable with said nonresilient portion.

3. A fusé cutout comprising a support having upper and lower line terminals, a double-pivot member pivoted to the support at one of its pivots, a fuse holder pivoted to said double-pivot member at its other pivot, an upper contact member on the fuse holder, a lower contact member slidably mounted upon the fuse holder 25 for longitudinal movement thereof from a retracted position to an extended position, said lower contact member being conductively engageable with the lower line terminal, means latching the double-pivot member by the lower 30 contact member when the latter is in its retracted position, means for holding a fuse link between the upper and lower contact members to retain the lower contact member in its retracted and latching position, a spring reacting 35 between said lower contact member and said fuse holder and biasing the lower contact member downward, a rotary link-tensioning member pivoted on the lower contact member and having a link-engaging saddle, said double-pivot member having a catch and said link-tensioning member having a hook engageable with the catch in a retracted position of the lower contact member and adapted to be held in engagement by an unbroken fuse link, and spring means biasing 40 said link-tensioning member to rotate in a direction to tension the fuse link and to release said hook from said catch when the link is severed.

4. Apparatus made according to claim 3, wherein the lower line terminal includes a nonresilient 50 arcuate conductive portion and wherein said lower contact member includes an arcuate spring engageable with said nonresilient portion.

5. The improvement in a fuse cutout of the class described having a fuse holder for a fuse link including a slidable member thereon movable between extended and retracted positions and having a pivoted member thereon swingable crosswise of the slidable member with cooperating means on the slidable and pivoted members locking the pivoted member only when the slid- 55 able member is in retracted position; comprising a pivoted link-extracting device on the slidable member which includes a hook engageable with a catch on the pivoted member when the slidable member is in retracted position, and a spring 60 biasing said link-extracting device toward release of the hook from the catch, said link-extracting device being adapted against spring bias 65 to be held in position wherein said hook engages said catch when the cutout carries an unsevered connected fuse link.
